HANDBAG ORNAMENT

Abraham Wirklich, New York, N. Y.

Application July 3, 1951, Serial No. 15,757

Term of patent 7 years

(Cl. D87—2)

To all whom it may concern:

Be it known that I, Abraham Wirklich, a citizen of the United States of America, residing in New York city, county of New York, and State of New York, have invented a new, original, and ornamental Design for a Handbag Ornament, of which the following is a specification, reference being had to the accompanying drawing, forming part thereof, wherein:

Figure 1 is a front elevational view of a handbag ornament, showing my new design.

Figure 2 is a side elevational view of the handbag ornament shown in Figure 1.

The rear of the handbag ornament is substantially plain in appearance.

I claim:

The ornamental design for a handbag ornament, substantially as shown and described.

ABRAHAM WIRKLICH.
